US00D583950S

(12) **United States Design Patent**
Itonaga et al.

(10) **Patent No.:** US D583,950 S
(45) **Date of Patent:** ** Dec. 30, 2008

(54) **PULSE WAVE MEASURING INSTRUMENT
WITH SPHYGMOMANOMETER**

(75) Inventors: **Kazunobu Itonaga**, Takatsuki (JP); **Toshihiko Ogura**, Kyoto (JP); **Tadashi Koike**, Kyoto (JP); **Yoshimi Niwa**, Kyoto (JP); **Atsushi Sato**, Kyoto (JP); **Naoki Mori**, Takatsuki (JP); **So Noguchi**, Hirakata (JP); **Shuji Tsuruta**, Ibaraki (JP); **Masayuki Kawai**, Hirakata (JP)

(73) Assignee: **Omron Healthcare Co., Ltd.**, Kyoto (JP)

(**) Term: **14 Years**

(21) Appl. No.: **29/302,805**

(22) Filed: **Jan. 24, 2008**

(30) **Foreign Application Priority Data**

Jul. 27, 2007 (JP) 2007-020396

(51) **LOC (8) Cl.** 24-02

(52) **U.S. Cl.** D24/165

(58) **Field of Classification Search** D24/165-169, D24/186; D10/98; 600/479-480, 485, 490, 600/493-495, 499, 500

(57) **CLAIM**

The ornamental design for a pulse wave measuring instrument with sphygmomanometer, as shown.

DESCRIPTION

FIG. 1 is a front perspective view of an embodiment of a pulse wave measuring instrument with sphygmomanometer showing our new design;

FIG. 2 is a rear perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a right side elevational view thereof; and,

FIG. 8 is a left side elevational view thereof.
